REFILL PEN

Kosei Iwasaki, Tokyo, Japan, assignor to Iwasaki Kinzo-ku Kogyo Company, Limited, Tokyo, Japan

Filed Oct. 22, 1969, Ser. No. 19,677

Claims priority, application Japan Apr. 24, 1969

Term of patent 14 years

Int. Cl. D19—06

U.S. Cl. D74—17

FIG. 1 is a perspective view of a refill pen showing my new design;

FIG. 2 is a front elevational view thereof as it appears with the writing point in retracted position.

FIG. 3 is a right side elevational view thereof;

FIG. 4 is a top plan view of FIG. 2; and

FIG. 5 is a bottom plan view thereof.

I claim:

The ornamental design for a refill pen, substantially as shown and described.
